L. E. HEILIG

GARAGE DOOR HOLDER

Filed April 8, 1925

UNITED STATES PATENT OFFICE.

LOUIS E. HEILIG, OF SHERMAN, CALIFORNIA.

GARAGE-DOOR HOLDER.

Application filed April 8, 1925. Serial No. 21,596.

To all whom it may concern:

Be it known that I, LOUIS E. HEILIG, a citizen of the United States, and resident of Sherman, Los Angeles County, State of California, have invented new and useful Improvements in a Garage-Door Holder, of which the following is a specification.

This invention relates to hardware, and more especially to a means for effectively holding a garage door open.

It is an object to provide an extremely simple, yet rugged and inexpensive device which may be easily attached to a swinging door in such a manner that the door may be opened without direct attention to the device, and an object is to provide a device which will automatically come into holding effect when the door has been opened to a desired or sufficient angle to allow ingress or egress. Also, an object is to provide a means which serves to hold the door in open position and prevents it from being opened beyond a necessary degree, as is sometimes desired.

An object is to provide a springless door holder, and to provide one which consists of but two special elements, each of very simple character and yet providing a reliable locking action and a readily operative releasing function.

Other objects and advantages will be made manifest in the following specification of an embodiment of the invention; it being understood that modifications, variations and adaptations may be resorted to within the scope and spirit of the invention as is here claimed.

Figure 1 is a perspective of the applied device shown on an open door.

Figure 2 is a plan showing the door closed.

In many cases in rows of garages, these are constructed so close that if the door of one garage is opened beyond an angle of 90 degrees to the front wall, the door will overlap the driveway of the next garage and this is often very objectionable. Again, doors of garages tend to blow closed very easily when standing out from the garage front. My invention is designed to eliminate these troubles.

The device comprises a preferably flat link 2 pivoted at its inner end on a hanger, bolt or lag screw 3 applied near the center of the header H in a doorframe. The outer end of the link is pivoted at 4 on the near end of a lever arm 5 having an elongated rock-shaft 6

which is vertically hung along the outer portion and on the inner face of a door D, vertically hinged at 7, on studs of the doorframe. The rock-shaft 6 is hung in suitable bearings 8.

The lever arm 5 is disposed near the top plane of the door so as to be fully clear of any vehicle running into or out of the garage.

The lower end of the rock-shaft has an outbent handle 9 and this may be retained in an outer position by a friction means, as the bearings 8, or a rest 10.

When the door is pulled open in the usual way the link 2 and the lever arm 5 straighten out and are forced past the dead center alignment or dead center of pivot 4. In such position a stop finger 5^a of lever 5 engages the link 2 and limits inward swing of the door until the handle 9 is pulled around by hand to break the dead lock of the link 2 and the lever 5. This allows the jointed ends thereof to buckle in to the position shown in Fig. 2 as the door closes.

What is claimed is:

1. A hinged door holder for over-head adaption to a garage door and comprising knuckle-jointed link and arm members one of which is pivotally connectible to a doorframe header, and the other of which has a rock-shaft attachable vertically to the door in such position that as the door opens to a desired angle the link and the arm elements straighten out and pass a dead center point, said link and arm members being at the upper end of the rock-shaft.

2. A hinged door holder comprising knuckle-jointed link and arm members one of which is pivotally connectible to a doorframe header, and the other of which has a rock-shaft attachable vertically to the door in such position that as the door opens to a desired angle the link and the arm members straighten out and pass a dead center point; the rock shaft having a handle on its lower end, whereby the said shaft may be rocked to unlock the link and the arm, said handle being disposed out of plane of the arm to permit the latter to move close to the door.

3. A hinged door holder comprising an elongated one-piece rock-shaft having a handle outturned from its lower end for ready access, and having a bent part forming a lever arm on its upper end disposeable just under a doorframe header and a link attachable at one end to the header and pivotally

connected to the swinging end of the arm; the latter having a stop finger to hold the link and the arm just past dead center alignment.

5. 4. The combination of a garage door having a vertical hinged edge, upper and lower bearings adjacent the outer, swinging edge of the door and on the inside thereof, a vertical rock-shaft mounted in said bearings and having an unlocking crank-handle disposed about waist high on the door for ready access, a link pivoted at one end to the door frame header, and an elongated lever arm bent over head from the upper end of the

rock-shaft and attached to the swinging end 15 of said link, and means for limiting movement of the link and the lever arm past dead center thereof.

5. A two-piece garage door holding device comprising a round-rod rock-shaft for 20 rotation in bearings and having at one end a short, angularly bent handle part and having at its other end an elongated lever arm formed of the rod shaft and having its remote end flattened, and a link member piv- 25 oted on the said flattened end of the arm.

LOUIS E. HEILIG.
